UNITED STATES PATENT OFFICE.

EMANUEL AUFIERO, OF BROOKLYN, NEW YORK.

DIRECTION-INDICATING DEVICE.

1,130,690.

Specification of Letters Patent.

Patented Mar. 2, 1915.

Application filed January 16, 1915. Serial No. 2,699.

To all whom it may concern:

Be it known that I, EMANUEL AUFIERO, a citizen of the United States, and a resident of Brooklyn, county of Kings, and State of New York, have invented new and useful Improvements in Direction-Indicating Devices, of which the following is a specification.

My invention relates to an improved indicating device for use on vehicles, whereby the driver may warn a following vehicle as to the direction in which he is going.

One of the objects of my invention is to provide a device of this class adapted to be effective both at night and in the day time.

A further object of the invention is to provide an indicator of this character which may be employed in connection with a "tail" lamp of the ordinary type and size. 20 In the accompanying drawing, showing one embodiment of my invention, Figure 1 is a partly sectional view of a tail lamp provided with a signaling indicator; Figs. 2 and 3 show a front view of one form of indicator occupying different positions; Fig. 4 shows in cross section a form of indicator which may be placed in the body of the vehicle to be operated in synchronism with the rear indicator. Fig. 5 shows in elevation the indicator illustrated in Fig. 4. Fig. 6 is one form of arrangement of tail lamp, actuating indicator and intermediate indicator placed in the tonneau of a limousine; and Fig. 7 is a front view of an operating indicator.

I find in practice that a two-color indicator adapted to be rotated on an arbor by means of Bowden wire or a flexible shaft, or by pneumatic or electrical means, is the most efficient signal for indicating the direction of movement of a vehicle, instead of using written signs, or a number of lamps of various colors adapted to be used in the night time only, as heretofore has been proposed.

When the two color indicator is made of suitable translucent material it may be combined with an ordinary tail lamp, thus furnishing an inexpensive and compact instrument useful in day time as well as in the night time.

In Fig. 6 I have illustrated a preferred form of my invention as applied to an automobile of the limousine type. As here shown my invention in its essential features consists of a tail light 41 attached to the

rear of the machine by the usual bracket and having its movable indicator controlled through a flexible Bowden wire from an operating device 44 attached to the steering post. In addition to the indicating device at the rear of the automobile I preferably provide a supplemental indicator 33 within the body of the vehicle to indicate to the occupants the proposed movement of the car.

In Figs. 1 to 5 and Fig. 7 are shown the details of construction of one form of my complete device. Fig. 1 shows the rear lamp which comprises the usual housing 14 containing the electric or other light 24. A bracket 16 is mounted in the housing and supports at its upper end a shaft 17 whose free end is centered in the crystal 13 of the lamp.

Attached to the end of the shaft 17 is a translucent disk whose operated halves 11 and 12 are differently colored, for instance, the part 11 will be white, the part 12 red. Engraved on the bevel of the crystal at 75 opposite sides are the words "right" and "left," and engraved at the top and bottom of the bevel are the words "going" and "stop" respectively, whereby the proposed movement of the car may be indicated by 80 turning the red portion of the disk adjacent the proper word on the crystal.

A preferred form of indicator which I have found highly satisfactory in practice consists of a disk of white glass of the kind 85 known to the trade as "opal" glass having one half of one surface covered with a substantial coat of translucent red enamel.

For operating the disk the end of the shaft 17 is provided with a pinion 19 which 90 is operated by a rack 20 mounted for vertical movement on the guide screw 21 set in the bracket 16. The rack 20 is connected to the end of the Bowden wire inclosed in its customary flexible casing 22' which extends into the car to the supplemental indicator 33. This indicator comprises a stationary casing 26 attached at a convenient point to the wall of the car and having a circular opening in its exposed face. In the 95 center of the wall opposite the opening a stud carrying a gear 30 is mounted for rotation and meshing with the gear is a rack 29 which extends across the casing and is connected at its opposite ends to the two sections 100 of the Bowden wire. The circular opening of the casing 26 is closed by a disk 28 at-

tached to the end of the stud of the gear 30 and across the face of the disk is set a sector-shaped colored pointer having its pointed end arranged to correspond in movement with the red portion of the disk of the lamp whereby the indications of the two devices will be the same.

The Bowden wire extends from the indicator 41 to the operator's device 44 on the 10 steering post. This device comprises a casing and pointer similar to the supplemental indicator within the car and having the gear of the pointer meshing with a rack attached to the end of the Bowden wire. To one edge 15 of the disk carrying the pointer an operating handle 45 is attached by means of which the chauffeur can turn the pointer to any desired position.

I regard the above described construction 20 as a superior and highly advantageous form of indicator. The opposite halves of "opal" and red produce a marked contrast by either transmitted or reflected light which can be distinguished for a long distance. Further, 25 as the entire area of the lamp crystal is occupied by effective contrasting parts of the indicating dial the size of the lamp is kept down and in fact need be no greater than the ordinary "tail" light to be visible for a 30 sufficient distance.

Having thus described my invention what I claim and desire to secure by Letters Patent is:—

1. In a direction indicator for automo-

biles, the combination of a lamp having a housing with an opening in one face thereof, a disk substantially filling said opening and rotatable about a center coincident with the center of said opening, said disk being translucent throughout its area and having on its exposed surface a design in different colors adapted to present a distinctive appearance in different positions of adjustment about its center, said colors presenting a contrasting appearance either by transmitted light from the lamp or by daylight and means operable by an occupant of said vehicle for rotatably adjusting said disk. 45

2. In a direction indicator for automobiles, the combination of a lamp having a 50 housing with a circular opening in one face thereof, a disk substantially filling said opening and rotatable about a center coincident with the center of said opening, said disk consisting of white translucent glass 55 and having a portion of its exposed surface covered with a translucent enamel of a color contrasting with the white of the uncovered portion and means operable by an occupant of said vehicle for rotatably adjusting 60 said disk.

Signed at Brooklyn, in the county of Kings and State of New York, this 14 day of Jan., 1915.

EMANUEL AUFIERO.
